CLAIM

The ornamental design for a scalpel, as shown and described.

DESCRIPTION

FIG. 1 is a left-side perspective view of a scalpel showing my new design.

FIG. 2 is a front view thereof.

FIG. 3 is a rear view thereof.

FIG. 4 is a right-side view thereof.

FIG. 5 is a left-side view thereof.

FIG. 6 is a top view thereof.

FIG. 7 is a bottom view thereof; and,

FIG. 8 is a front perspective view thereof when in use.

(Continued)

The human hand rendered in short broken lines in FIG. 8 illustrates environmental subject matter intended to assist in showing how the design appears when in use and forms no part of the claim.
